(57) **CLAIM**

The ornamental design for a window of a binder, as shown and described.

DESCRIPTION

FIG. 1 is an isometric outside view of a window of a binder. FIG. 2 is an isometric inside view of the window of a binder of FIG. 1.

FIG. 3 is an inside top plan view of the window of a binder of FIG. 1.

FIG. 4 is an outside top plan view of the window of a binder of FIG. 1.

FIG. 5 is a first end view of the window of a binder of FIG. 1.

FIG. 6 is a second end view of the window of a binder of FIG. 1, the first end view opposite the second end view.

FIG. 7 is a first side view of the window of a binder of FIG. 1.

FIG. 8 is second side view of the window of a binder of FIG. 1.

FIG. 9 is an enlarged inside top view of the window of a binder of FIG. 1, including the window insert.

FIG. 10 is an enlarged cross-sectional view of the window of a binder taken along lines 10-10 of FIG. 9, including the window insert.

FIG. 11 is an enlarged inside top view of the window of a binder of FIG. 1, excluding the window insert.

FIG. 12 is an enlarged cross-sectional view of the window of a binder taken along lines 12-12 of FIG. 11, excluding the window insert.

FIG. 13 is an isometric view of the window of a binder shown in FIG. 12; and,

FIG. 14 is an enlarged inside top plan view of the window insert of the window of a binder of FIG. 1.

The broken lines showing of the binder represents the environment of the claimed design and forms no part thereof. The broken lines in the drawings illustrate portions of the window of a binder and form no part of the claimed design.

1 Claim, 7 Drawing Sheets
